SAFETY RAZOR AND BLADE

Yervant H. Kurkjian, Paterson, N. J., assignor to
 American Safety Razor Corporation, Brooklyn, N. Y., a corporation of Virginia

Application January 4, 1935, Serial No. 435

11 Claims. (Cl. 30—70)

This invention relates to razors and more particularly to safety razors.

An important object of this invention is the production of a safety razor blade which may be of material thickness and at the same time freely flex throughout its transverse area when placed within a holder and conform to the contour of the holder when the blade is clamped in position within a holder without danger of breaking.

Another object of this invention is the production of a relatively thick safety razor blade having elongated slots extending across the transverse area of the blade to a point in close proximity to the cutting edge of the blade, whereby the blade may freely flex throughout its transverse area to conform snugly to the transverse contour of the holder upon which the blade is mounted.

Another object of this invention is the production of a simple and efficient relatively thick razor blade having slots arranged in close relation across the transverse area of the blade and terminating at a point in close proximity to the cutting edge of the blade whereby a relatively narrow and stiff strip of metal will be provided along the cutting edge of the blade and at the same time permit the blade throughout its transverse area to flex and snugly conform to the transverse contour of a holder upon which the blade may be mounted.

A still further object of this invention is the production of a simple and efficient safety razor blade comprising a holder consisting of a plurality of sections having interfitting ribs and sockets extending approximately across the entire transverse area of the holder, and a blade which is provided with slots extending to a point in close proximity to the cutting edge of the blade, the ribs being adapted to fit within the slots of the blade whereby the blade may be firmly braced and anchored within the holder and at the same time held in flexed fitted relation within the transverse contour of the holder.

Other objects and advantages of the present invention will appear throughout the following specification and claims.

In the drawing:—

- Figure 1 is a side elevation of the improved razor and blade attached thereto;
- Figure 2 is a vertical sectional view taken on line 2—2 of Figure 1;
- Figure 3 is a transverse sectional view taken on line 3—3 of Figure 2;
- Figure 4 is a vertical sectional view taken on line 4—4 of Figure 2;

Figure 5 is a bottom plan view of the outer section of the blade holder;

Figure 6 is a top plan view of the improved blade;

Figure 7 is a top plan view of the inner section of the blade holder; and

Figure 8 is a vertical sectional view through a modified form of blade holder.

By referring to the drawing, it will be seen that the blade holder comprises preferably an outer section 10 and an inner section 11. The outer section 10 may be formed of relatively thin metal arranged in concavo-convex formation in transverse section, the outer section 10 having formed integral upon its inner face a plurality of relatively closely arranged transversely extending ribs 12, which ribs extend across substantially the entire transverse area of the outer section 10, as will be clearly noted by considering Figures 3 and 4. These ribs 12, however, terminate short of the outer side marginal edges 13 of the outer section 10, as shown in Figures 3 and 4, and each rib 12 is provided with an abutment shoulder 14 spaced slightly inwardly of the marginal edges 13. The ribs 12 are preferably bowed or curved to follow the contour of the section 10.

The inner section 11 of the holder may be formed in the conventional manner common to safety razors wherein the inner section 11 may be provided with the usual guard or protector means 16 along the side edges. The inner section 11, however, is provided with a plurality of convex channels 17 upon its upper face in such a position as to snugly receive the curved lower faces of the ribs 12 of the outer section 10. These ribs 12 are adapted to snugly fit within the channels or sockets 17 of the inner section 11 of the holder and thereby firmly anchor the inner and outer sections together and hold these sections against lateral shifting or vibration thereby producing a very sturdy holder having interlocking features which will make the holder a very sturdy blade-engaging and holding means. These ribs 12 and the sockets 17 are arranged in close relation across the transverse area of the sections 10 and 11 of the holder as is clearly illustrated in Figures 5 and 7.

A specially constructed blade 18 is employed in connection with this blade holder, and this blade 18 comprises an elongated body, which body is also provided with closely arranged transversely extending slots 19, which slots 19 extend substantially across the entire transverse area of the blade 18 leaving only transversely extending ribs 19a between the slots, and a relatively narrow

stiff strip 20 near each cutting edge 21. Because of this particular type of blade it is possible to use a type of steel which is considerably thicker or of heavier gauge than is ordinarily possible in a flexible blade of a type commonly used in safety razors. In fact, it has been found practical and of great advantage to utilize steel of two or three times the thickness used in the present flexible safety razor blade. Consequently, the stiffness of the blade adjacent the cutting edge thereof will reduce vibration and distortion of the blade to a minimum, and because of the interlocking feature of the inner and outer sections of the holder and the fitting of the ribs 12 within the slots 19 of the blade 18, a very compact, firmly clamped structure is produced providing a stiff, well-backed blade with a very rigid cutting edge.

As shown in Figure 4, the outer section 10 may be clamped in position in a manner common to the trade, through the medium of the handle 22 engaging the threaded extension 23, which threaded extension is carried by the outer section 10 and extends through the aperture 24 of the inner section 11.

By carefully considering Figure 3 and Figure 4 it will be particularly noted that the ribs 12 are adapted to firmly and snugly fit within the slots 19 of the blade and also snugly fit within the slots or channels 17 of the inner section 11. The inner section 11 is provided with a ledge portion 25 adjacent the side marginal edges, which ledge portion is relatively narrow and is arranged along the ends of the sockets 17. These ledge portions extending along each side of the inner section 11 will provide a very efficient rest for the relatively narrow stiff strip 20 along each side of the blade 18, which relatively narrow stiff strip will be firmly clamped also by the side marginal edges 13 of the outer section 10. In this way the blade 20 will be not only efficiently reinforced through the medium of the interfitting lugs 12 and the sockets 17 and the passing of the lugs through the slots 19, but the relatively narrow and stiff strip 20 along the side edges of the blade 20 will be firmly clamped thereby firmly and rigidly holding the blade in a firmly clamped position throughout its entire transverse area and allowing the blade to conform throughout its entire transverse area to the contour of the adjacent faces of the inner and outer sections of the holder. By means of this structure described, the blade will not be gripped at only one point or at two points, but it will be firmly engaged throughout its entire transverse area with the exception of its extreme cutting edges which project beyond the holder.

Because of the reinforcing ribs formed on the outer section, it will be possible to construct the body of the outer section of extremely thin metal, thereby permitting the blade to be brought close to the outer face of the outer section.

It is well recognized in the art of cutlery that a blade made of stiff material preferably thick and rigidly held or braced, will not vibrate and produce a wavy cutting edge while shaving. Because of the particular type of blade illustrated and described, I have eliminated the possibility of this waving action, and have provided means for sturdily and firmly anchoring the blade in position, permitting the blade to be made of relatively thick material, and at the same time because of its construction, the blade may be freely flexed in order that the blade may conform completely throughout its entire transverse area with

the exception of its cutting edges, with the transverse contour of the blade holder.

In Figure 8, there is shown a modified form of the invention wherein a holder is illustrated embodying an inner section 30 upon which is hingedly secured an outer section 31, the outer section 31 being preferably of thin material and being concavo-convex in cross-section and curved inwardly toward the inner section 30. The outer section 31 is provided with ribs 32 similar to the ribs 12 previously described, which ribs 32 fit in the channels 33 formed in the inner section 30 and extend through transversely extending slots 34 formed in the blade 35 which are similar to the slots 19 in the blade 18. A suitable manipulating handle 36 of the conventional type may be employed for holding the inner and outer sections in clamped relation. The purpose of Figure 8 is merely to show the adaptation of my structure to a different type holder, but the holder is specially constructed by having the outer face concave or dished in order to present a concave surface upon the face when shaving and allow the cutting edge of the blade to come into close contact with the face and eliminate as much friction as possible. Furthermore, the ribs 32 will firmly brace the outer section 31 and because of the particular assembly, as shown in this figure, and in the preferred embodiment, the parts will be clamped in one composite mass. This concave structure will prevent the rocking of the holder upon the face while shaving, and the holder will contact with the face at two extreme points along the side edges of the holder allowing the shaver to feel this particular contact.

By noting particularly Figure 6, it will be seen that the slots 19 cut in the blade 18, will define transversely extending flexible bracing ribs 19a, which extend substantially across the entire transverse area of the blade firmly bracing the cutting edges of the blade and at the same time providing a completely unitary structure permitting the thickness of the material used in the blade to be varied, and at the same time permitting the blade to freely flex to conform to the transverse contour of the holder, this being made possible because of the flexible yet sturdy ribs 19a.

It should be understood that certain detail changes in the construction may be employed without departing from the spirit of the invention, so long as such changes fall within the scope of the appended claims.

Having described the invention, what I claim as new is:—

1. In combination with a razor blade holder of the safety razor type embodying a plurality of razor blade clamping sections, a blade adapted to be interposed between the sections, said blade being provided throughout substantially its entire extent with a plurality of closely arranged elongated transversely extending slots terminating at a point closely approximating the cutting edge of the blade, one of the sections of the holder having a plurality of transversely extending elongated ribs adapted to fit through the slots in the blade for anchoring the blade in position and bracing and reinforcing the blade, the other section of the holder having sockets for receiving said ribs, means for clamping the sections together whereby the blade will be held in clamped relation between the sections of the holder and whereby the blade may be freely flexed to conform snugly to the transverse contour of the holder.

2. In combination with a razor blade holder

of the safety razor type embodying a plurality of razor blade clamping sections, a blade adapted to be interposed between the sections, said blade being provided with a plurality of closely arranged transversely extending elongated slots terminating at a point closely approximating the cutting edge of the blade, one of the sections of the holder having a plurality of transversely extending ribs adapted to fit through the slots in the blade for anchoring the blade in position and bracing and reinforcing the blade, the other section of the holder having sockets for receiving the ribs, means for clamping the sections together whereby the blade will be held in clamped relation between the sections of the holder and whereby the blade may be freely flexed to conform snugly to the transverse contour of the holder, the slots in the blade providing a relatively narrow stiff strip adjacent the cutting edge of the blade, and the sections of the holder being held in clamping engagement with said strip to firmly hold the blade against vibration, the assembly providing a composite mass when arranged in clamped relation.

3. In combination with a holder consisting of a plurality of sections, a relatively thick flexible razor blade having a cutting edge, said blade being provided with a plurality of closely arranged transversely extending slots terminating in close proximity to the cutting edge of the blade and extending substantially over the entire area of the blade whereby a relatively thick blade may be freely flexed to conform to the transverse contour of the holder, the sections of the holder being provided with interfitting concavo-convex portions for snugly receiving the flexible blade, one section having a plurality of closely arranged transversely extending ribs, the ribs extending substantially across the entire transverse area of the last mentioned section, the other section having sockets for receiving the ribs, and means for clamping the sections together.

4. In combination with a holder consisting of a plurality of sections, a relatively thick flexible razor blade having a cutting edge, said blade being provided with a plurality of closely arranged transversely extending slots terminating in close proximity to the cutting edge of the blade and extending substantially over the entire area of the blade whereby a relatively thick blade may be freely flexed to conform to the transverse contour of the holder, the sections of the holder being provided with interfitting concavo-convex portions for snugly receiving the flexible blade, one section having a plurality of closely arranged transversely extending ribs, the ribs extending substantially across the entire transverse area of the last mentioned section, the other section having sockets for receiving the ribs, and means for clamping the sections together, said ribs having abutment shoulders for engagement with the ends of said slots formed in the blade whereby the cutting edge of the blade will be firmly braced throughout its extreme transverse area.

5. A safety razor of the class described comprising a plurality of sections, one section having a plurality of transversely extending ribs, the other section having a plurality of transversely extending sockets adapted to receive the ribs, a flexible blade fitted between the sections and being provided with a plurality of elongated transversely extending slots for fitting over said ribs whereby the blade will be held in an anchored position between the sections, and the outer face of one of the sections being concave to present

a two-point contact upon the face while the razor is in operation.

6. A razor of the class described comprising an outer section and an inner section, a blade adapted to be clamped between said sections, said outer section having a plurality of inwardly extending closely arranged elongated ribs, the ribs extending transversely across the face of the outer section and terminating short of the marginal edges thereof, the blade being normally flat and having transverse slots for receiving said ribs, the under faces of the ribs being continuously curved along their length to facilitate the insertion of the ribs through said slots, said inner section having sockets for receiving said ribs, and means for clamping the sections together.

7. A razor of the class described comprising an outer section and an inner section, a blade adapted to be clamped between said sections, said outer section having a plurality of inwardly extending closely arranged elongated ribs, the ribs extending transversely across the face of the outer section and terminating short of the marginal edges thereof, the blade being normally flat and having slots for receiving said ribs, the under faces of the ribs being curved so that they present their concave side toward the blade, whereby their ends will enter the slots in the blades before their inner portions, to facilitate the insertion of the ribs through said slots, said inner section having sockets for receiving said ribs, and means for clamping the sections together.

8. In a safety razor having a holder and a blade mounted therein, said holder having its upper surface concaved transversely whereby when it is laid on a flat surface, it will have two spaced lines of contact therewith, and means for holding said blade in said holder so that said blade protrudes from the holder to such an extent and at such an angle that when said concaved upper surface is laid on a flat surface, the cutting edge of said blade will be in shaving position in relation to said surface.

9. A safety razor comprising a holder having a concave blade seat, and a clamping member adapted to cause a normally flat blade to assume a concave contour and to hold said blade against said seat with its shaving edge protruding from said holder, said clamping member having a concave blade engaging surface, and an upper concave surface substantially parallel to said blade, and the arc of curvature of said blade and holder being such that when said upper concave surface of said clamping member is laid on a flat surface, said shaving edge will be in shaving relation to said flat surface.

10. In combination with a razor blade holder of the safety razor type embodying a plurality of razor blade clamping sections, a blade adapted to be interposed between the sections, said blade being provided throughout substantially its entire extent with a plurality of closely arranged elongated transversely extending slots terminating at a point closely approximating the cutting edge of the blade, one of the sections of the holder being curved in transverse section and having a plurality of transversely extending elongated ribs adapted to fit through the slots in the blade for anchoring the blade in position and bracing and reinforcing the blade, the other section of the holder being curved in transverse section so as to be complementary to the first-mentioned section and having sockets for receiving said ribs, means for clamping the sections together whereby the blade will be held in clamped relation between the sections of the holder and

whereby the blade may be freely flexed to conform snugly to the transverse contour of the holder.

11. In a safety razor having a holder and a blade mounted therein, said holder having its upper surface concaved transversely, whereby, when it is laid on a flat surface, it will have two spaced lines of contact therewith, and means for holding said blade in said holder so that said blade protrudes from the holder to such an ex-

tent and at such an angle that when said concaved upper surface is laid on a flat surface, the cutting edge of said blade will be in shaving position in relation to said surface and said holder and holding means having portions thereof opposed and engaging said blade continuously along an area extending parallel to and adjacent the cutting edge thereof.

YERVANT H. KURKJIAN. 10
